UNITED STATES PATENT OFFICE

HERBERT A. VOS, OF NEW YORK, N. Y.

DESIGN FOR A DISPLAY STAND

Application filed February 18, 1932. Serial No. 42,919. Term of patent 7 years.

To all whom it may concern:

Be it known that I, HERBERT A. Vos, a citizen of the United States, residing at New York city, county of Bronx, borough of Bronx, and State of New York, have invented a new, original, and ornamental Design for a Display Stand, of which the following is a specification, reference being had to the accompanying drawings, forming a part thereof.

I claim:

The ornamental design for a display stand as shown.

HERBERT A. VOS.
